Primary Examiner — Shawn T Gingrich*Assistant Examiner* — Bryan N. Melvin*(74) Attorney, Agent, or Firm* — InHouse Co. Law Firm;
Theodore S. Lee, Esq.(57) CLAIM

The ornamental design for lamp wick, as shown and described.

DESCRIPTION

FIG. 1 is a front view of a lamp wick showing the novel design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines in the drawings illustrate portions of the lamp wick that form no part of the claimed design.
